BRACKET FOR CURTAIN RODS

Filed Jan. 15, 1931

UNITED STATES PATENT OFFICE

WALTER H. TOELLE, OF WALLINGFORD, CONNECTICUT, ASSIGNOR TO H. L. JUDD COMPANY, INC., OF WALLINGFORD, CONNECTICUT, A CORPORATION OF DELAWARE

BRACKET FOR CURTAIN RODS

Application filed January 15, 1931. Serial No. 508,917.

My invention relates to a bracket for curtain rods particularly, but not exclusively, adapted for supporting the ends of such rods.

It is the principal object of the present invention to provide a new and improved bracket for curtain rods, which is cheap to manufacture, serviceable in use, easy to apply, having comparatively few parts, and which will securely hold the curtain rod in place.

Other objects and features of the invention will be pointed out or will become apparent upon a reading of the specification.

In the drawing which shows, for illustrative purposes only, a preferred form of the invention—

Fig. 1 is a plan view of a curtain rod which is supported at the ends by brackets which embody features of my invention;

Fig. 2 is a front elevation of the curtain rod and brackets shown in Fig. 1;

Fig. 3 is a transverse section taken upon the plane of the line 3—3 in Fig. 2 showing a side view of the bracket;

Fig. 4 is a plan view of a modified form of my invention;

Fig. 5 is a front elevation of the device shown in Fig. 4;

Fig. 6 is a transverse section taken upon the plane of the line 6—6 in Fig. 5, and showing a side view of the bracket shown in Figs. 4 and 5.

In said illustrative drawing, 10 represents a curtain rod. My invention is shown embodied in the brackets which support the rod at each end thereof. Each of these brackets is made in two parts, one being a bracket member 11 which is adapted to be attached to a wall, the other being a curtain rod holder 12 which is adapted to embrace the end of the curtain rod 10 and to be removably secured to the bracket member 11.

In Figs. 1, 2, and 3, the rear end of the bracket member 11 is bent at right angles to the member so as to form a laterally extending ear which is adapted to bear against a wall, and which may be secured to the wall by any convenient means, as by screws. The front end of the bracket member 11 is preferably channel-shaped so as to form a ver-

tical channel 13 which forms a pocket for the reception of the end of the rod holder 12. The rod holder 12 is adapted to be secured to the curtain rod 10. In the form shown in the drawing the curtain rod is held by friction in an opening in one end of the holder. The other end of the rod holder 12 conforms in shape to the channel 13 in the bracket member 11. One of the members 11 and 12 has a tongue which is adapted to fit in a suitable recess in the other of these members. In the form shown in the drawing, the rod holder 12 has a downwardly extending tongue 15 which functions as an offset lug adapted to fit within a pocket 14 in the bracket member 11 adjacent to the recess therein. One or two curtain rod pulleys 16 are pivoted at 17 to the rod holder 12. 18 is a separator which is employed when two pulleys 16 are used for the purpose of keeping separate the portions of the curtain cord passing over the two pulleys. Suitable means, such as a rivet 19, are employed to prevent the rod 10 from coming in contact with the pulleys 16. Holes 20 in the pocket 14 and in the tongue 15 register with each other so that when a curtain supporting hook is passed through these holes the bracket member 11 and the rod holder 12 will be locked together.

When the parts are assembled as in Figs. 1 and 2 it will be seen that the walls of the channel 13 hold the end of the holder 12 from displacement forward or backward while the tongue 15 resting in the pocket 14 supports the holder 12 and also prevents the holder from escaping from the channel 13.

In the modified form of my invention shown in Figs. 4, 5, and 6, 21 represents a curtain rod. The bracket consists of two parts, one of which is a bracket member 22 which is adapted to be attached to a wall, and the other of which is a rod holder 23 which is adapted to embrace the end of a curtain rod and to be removably secured to the bracket member 22. The rear end of the bracket member 22 is bent so as to form a laterally extending ear which is adapted to bear against a wall and be secured thereto by any convenient means. At the front end of the member 22 is a channel formed by two up-

wardly extending arms 24—24 which conform in contour to a portion of the exterior of the rod holder 23, the extreme ends of the arms 24 being turned in slightly to grip the holder 23. These arms have sufficient 5 springiness so that the rod holder can be forced between the inturned ends of the arms 24 so that the holder will make a snug fit with the member 22. The rod holder 23 is adapted to be secured to the rod 21. In the 10 form shown in the drawing the curtain rod is held by friction in an opening in one end of the holder. The other end of the rod holder 23 is adapted to bear against the bracket member 22. One of the members 22 and 23 has a tongue which is adapted to fit in a suitable recess in the other of these members. In the form shown in the drawing, the rod holder 23 has a downwardly extending lug or tongue 26 which is adapted to pass through 15 a slot 25 in the bracket member 22. The turned in ends of the arms 24 prevent the unintentional dislodgment of the part 26 from the bracket. Attached to the rod holder 23 are two or three plates 27 to which are pivoted one or two curtain cord pulleys 28 by 20 means of the pivot 29. A hole 30 is provided in the tongue 26 so that when a curtain supporting hook 31 (see Fig. 2) is passed through the hole 30 the rod holder 23 will be 25 locked to the bracket member 22.

While the invention has been described in considerable detail and specific forms embodied in end supports for curtain rods have 30 been shown in the drawing, it is to be understood that the invention may be otherwise embodied and employed in connection with brackets for curtain rods and the like of various types other than herein shown.

40 I claim:

1. A bracket for curtain rods comprising, a bracket member adapted to be attached to a wall, and a rod holder adapted to be secured to a curtain rod, one of said members having a tongue thereon adapted to cooperate with a recess in the other of said members.

2. A bracket for curtain rods comprising, a bracket member adapted to be attached to a wall, and a rod holder adapted to be secured 50 to a curtain rod, one of said members having a tongue thereon adapted to cooperate with a recess in the other of said members, and one of said members having a channel therein which fits a portion of the exterior of the 55 other of said members.

3. A bracket for curtain rods comprising, a bracket member adapted to be attached to a wall and having a channel therein and having a tongue receiving portion, and a rod holder adapted to fit within said channel and having a tongue adapted to cooperate with said tongue receiving portion so that said rod holder may be removably secured to said bracket member.

65 4. A bracket for curtain rods comprising,

a bracket member adapted to be secured to a wall, and a rod holder adapted to be secured to a curtain rod and having a curtain cord pulley within said holder and having a tongue adapted to cooperate with said bracket member so that said rod holder may be removably secured to said bracket member. 70

5. A bracket for curtain rods comprising, a bracket member, and a rod holder adapted to be attached to the end of a curtain rod and having two curtain rod pulleys within said holder and having a separator between said pulleys and having a tongue which cooperates with said bracket member so that said rod holder can be removably secured to said 80 bracket member.

6. A bracket for curtain rods comprising, a bracket member adapted to be attached to a wall and having a slot therein, and a curtain rod holder having a tongue thereon which is adapted to cooperate with the slot in said bracket member so that said rod holder can be removably secured to said bracket member. 85

7. A bracket for curtain rods comprising, a bracket member having a slot therein, a curtain rod holder having a curtain cord pulley therein and having a tongue thereon which is adapted to coact with said slot in said bracket member so that said rod holder can be removably secured to said bracket member. 90

8. A bracket for curtain rods comprising, a bracket member having a slot therein and having a pair of upwardly extending arms, and a curtain rod holder adapted to fit between the upwardly extending arms of said bracket member and having a tongue thereon which is adapted to engage the slot in said bracket member so that said rod holder can be removably secured to said bracket member. 100

9. A bracket for curtain rods comprising, a bracket member having a slot therein and having a pair of upwardly extending arms, and a rod holder adapted to be engaged by said upwardly extending arms on said bracket member and having a curtain cord pulley attached thereto and having a tongue adapted to pass through said slot in said bracket member so that said rod holder can be removably secured to said bracket member. 110

10. A bracket for curtain rods comprising, a bracket member adapted to be attached to a wall, and a rod holder adapted to be secured to a curtain rod, one of said members having a tongue thereon adapted to fit within a recess in the other of said members, said members having registerable holes therein through which a curtain supporting hook can be passed to lock said members together. 120

11. A bracket for curtain rods comprising, a bracket member adapted to be attached to a wall and having a pocket therein, and a rod holder adapted to be secured to the outer end of a curtain rod and to fit in said pocket in said bracket member, and a locking lug de- 125

pending from said holder and coacting with said bracket to secure said holder against endwise escape from said pocket.

12. A bracket for curtain rods comprising a bracket member adapted to be attached to a wall and having a slot therein, and a rod holder adapted to be secured to a curtain rod and to fit in said slot in said bracket member, said members having registerable holes therein through which a curtain supporting hook can be passed to lock said members together.

13. A bracket for curtain rods comprising a bracket member adapted to be attached to a wall and having a pocket therein, a rod holder adapted to be secured to the outer end of a curtain rod and to fit in said pocket in said bracket member, a locking lug depending from said holder and coacting with said bracket to secure said holder against endwise escape from said pocket, and means to prevent the unintentional dislodgment of said lug from said bracket.

14. A support for curtain rods comprising a bracket member adapted to be attached to a wall and having a pocket therein for a rod holder, a rod holder adapted to be secured to the end of a curtain rod and to fit into said pocket in said bracket, and a tongue extending downwardly below said holder and co-operating with a portion of said bracket member to hold said rod in removable engagement with said bracket member.
